CLAIM

We claim the ornamental design for a portable information handling system, as shown and described.

DESCRIPTION

FIG. 1 is a front perspective view of the portable information handling system in an open configuration.

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a perspective view of the portable information handling system with the housing rotated to a first closed configuration; and,

FIG. 9 is a front perspective view of the portable information handling system with the housing rotated in the opposite direction into a second closed configuration.

Broken lines shown in the drawings illustrate portions of the portable information handling system, and form no part of the claimed design.

1 Claim, 7 Drawing Sheets
